UNITED STATES PATENT OFFICE

SVEN LARSSON, OF SANDVIKEN, SWEDEN

FEEDING ARRANGEMENT IN SHARPENING MACHINES FOR RAZOR BLADES

Application filed April 13, 1928, Serial No. 269,829, and in Sweden April 14, 1927.

This invention relates to such a machine, where the blades, which are to be sharpened, are carried to the sharpening member by means of a conveyor for instance a chain or a belt, on which are fastened catching members such as projections or pins which suit corresponding holes in the blade.

The purpose of the invention is to cause an automatic feeding of the blades.

10 The invention is mainly characterised thereby that the blades arranged in a pile are arranged one by one to be shoved down against the belt at a certain angle to this by means of a suitable, mechanically actuated member, in order that one of the catching members on the belt may at the forward movement of the belt automatically catch into the hole at the forward end of the blade and that each blade is arranged by the pulling 20 forward to be pressed down against the belt by the weight of the pile or the like, whereby the hole at the other end of the blade is placed over the next following catching member on the belt.

25 Two embodiments taken as examples of the invention are shown in the accompanying drawings. Herein is Fig. 1 a side view partly in section of the feeding arrangement according to the one embodiment, Fig. 2 shows 30 certain parts shown in Fig. 1, seen in plan, and Fig. 3 is a vertical cross section of Fig. 1. Fig. 4 shows a side view partly in section of the other embodiment of the feeding arrangement.

35 In the embodiment according to Figs. 1-3 the endless belt or chain is indicated by 1. This is fed in the direction of the arrow *a* with the aid of two guiding or chain wheels 36, only one of which is partly shown in Fig. 40 4. The belt or chain is provided with projections or catching members such as pins 2. Between these pins the chain is provided with 45 holes 3, which by catching round projections 4 projecting from the circumference of a wheel 5 set this wheel in motion. The wheel 5 is loosely journaled on a shaft 6. On the same shaft on a turnable sleeve 7 is journaled an arm 8, which by means of its prong shaped end 9 grips journals 10 projecting 50 from said sleeve 7. The arm 8 can thus be

turned around the shaft 6 and as well swung around the journals 10 in a plane coinciding with the lengthwise direction of the shaft 6. The arm 8 is provided at the top with a groove 11 for an arm 12, which projects from an arm 13, which is also turnably journaled on the shaft 6 with the help of a sleeve shaped hub 14. The arm 12 serves to guide the arm 8 during its swinging in the axial plane of the shaft 6. A spring 15 connects the arms 60 12 and 13. From this latter projects an arm 16, to which a spring 17 is fastened, which with its other end is fastened in the frame 18 and normally holds the arm 13 and thereby the arm 8 in its right end position (not shown) in Fig. 1. On the wheel 5 teeth 19 are arranged in a circle, which teeth during the turning of the wheel by means of the belt 1 can grip the arm 8 and against the action of the spring 17 can swing the arm downwards to the left (Fig. 1).

On the frame in a suitable holder 20 is arranged a piston rod 21, movable in holes 22, 22¹ in the holder 20. The piston rod is provided with a cross piece 23 and a piston 24. 75 The cross piece is provided with two springs 25, which in a suitable way (Fig. 2) are fastened to the frame and try to pull the cross piece with the piston to the left in Fig. 1. The forward piece 37, which supports the springs 25, is omitted in Figs. 1 and 4. Two shoulders 26, 27 hereby limit the movements of the cross piece 23. The piston 24 itself runs into a discharging canal 28 for the razor blades, which in the form of a pile 29 are arranged in a magazine or a receptacle 30. A weight 31 serves to press the blades down in the path of the piston. The lowermost blade just being discharged is indicated by 32. A guide 33 is under the influence of a spring 34 movable up and down in relation to the blade being fed.

80 The arrangement works in the following manner.

At the pulling forward of the belt 1 in 95 the direction of the arrow *a* the wheel 5 is caused to rotate by means of the holes 3 and the catching members 4. By the teeth 19 on the wheel 5 the lever 8 is caused to participate in the movement, whereby the piston rod 100

21 with its piston 24 is released and by the springs 25 is shoved axially in an oblique direction down towards the belt 1, thereby shoving the bottom blade 32 in the pile 29 in front 5 of it. When the blade is shoved down in such a position, that the catching member 2¹ on the belt 1 at its forward movement can catch into the forward hole on the blade, the cross piece 23 of the piston rod comes to rest 10 against the shoulder 27 and prevents further shoving down of the blade. At the same time as the lever 8 is moved by the teeth 19, it is moved from the wheel 5 by the shoulder 35, whereby the same in a certain position, 15 directly after the blade is fully shoved down, is released and pulled back in to initial position by the spring 17, whereby the piston rod is also pulled back in to initial position. At the pulling forward of the blade by the 20 pin 2¹ it is pressed at the same time down against the belt 1 by the spring 34 and the guide 33, whereby the next following hole in the blade comes on the next following catching member 2 on the belt.

25 The embodiment shown in Fig. 4 differs from that earlier described only therein, that the blades are here fed on the belt 1 by the passing of this over the conducting- or guiding wheel 36. The wheel 5 is hereby driven 30 in a suitable manner from the belt 1 or from the conducting- or guiding wheel, but in an opposite direction from that in Fig. 1.

35 The manner of working is for the rest like that described in the first embodiment, where- 40 by however the springs 25 are here tensioned during the moving of the wheel 5 and the arm 8 by the belt and guiding wheel respectively and at the releasing of the arm 8, they cause it and the piston rod to snap back to the left (Fig. 4) for the discharging of a 45 blade. The spring 17 is omitted by this embodiment.

It is evident, that by both embodiments the 45 blades are fed on to the belt or chain in oblique direction towards this.

It should be noticed, that the shown embodiments are only taken as examples and that the object of the invention may be modified in many ways without deviating from the 50 principle of the invention. For instance one may instead of the springs (for instance 17, 25) use hydro- or pneumatic power.

Having now described my invention, what 55 I claim as new and desire to secure by Letters Patent is:

1. A feeding mechanism comprising a movable conveyor, a magazine to contain articles, a piston to displace the articles toward the conveyor, said piston having a cross-piece, 60 a shaft loosely supporting a feed wheel having means for its rotation by the conveyor, an arm pivoted on the shaft for shifting movement in the plane of the shaft axis and having engagement with the cross-piece, resilient 65 means respectively urging the piston and arm

in opposite directions, the resilient means of the arm being more powerful thus to hold the piston in a retracted position, arm-engaging means on the wheel to engage and rock the arm against the tension of its resilient means thus yielding to the resilient means of the piston for a movement of the piston to displace an article, and a cam over which the arm rides to shift it on its pivot for disengagement of the arm from said arm-engaging means and a return of the arm and piston to the original position.

2. In a feeding mechanism, a reciprocable piston having a cross-piece with connected resilient means tending to move the piston in one direction, a shaft, a pair of arms in engagement with the cross-piece, one of the arms being journaled on the shaft and having connected resilient means tending to rock both arms in the opposite direction, a sleeve to which the other arm is pivoted and which is mounted on the shaft, a slip connection between the arms causing them to rock together, arm-engageable means engageable with one arm thus to rock both arms against the tension of the respective resilient means so that the piston can make a working stroke, and means for shifting said arm by virtue of said slip connection for disengagement thereof from said arm-engaging means and a return of both arms and the piston to the original position.

In witness whereof, I have hereunto signed my name.
